UNITED STATES PATENT OFFICE.

ALBERT O. COULLIARD, OF MILFORD, MASSACHUSETTS.

GAME APPARATUS.

1,387,241.

Specification of Letters Patent.

Patented Aug. 9, 1921.

Application filed December 14, 1920. Serial No. 430,642.

To all whom it may concern:

Be it known that I, ALBERT O. COULLIARD, a citizen of the United States, and a resident of Milford, county of Worcester, and 5 State of Massachusetts, have invented a new and Improved Game Apparatus, of which the following is a full, clear, and exact description.

This invention relates to improvements in 10 game apparatus, particularly to that form of game apparatus in which the operator endeavors to assemble certain eccentrically movable members within a fixed space on a field.

15 An object of the invention is to provide an apparatus in which great skill on the part of the operator will be required to assemble these members.

20 A further object is to provide a game apparatus which will be neat and attractive in appearance, which will prove interesting and amusing, and which will be comparatively inexpensive to manufacture.

25 With these and other objects in view, the invention consists in certain novel features of construction and combinations and arrangements of parts, as will be more fully hereinafter described and pointed out in the claim.

30 In the accompanying drawings:

Figure 1 is a top plan view of my improved game apparatus.

Fig. 2 is a view in transverse section through one end of the box.

35 Referring in detail to the drawing, 1 represents a square game board, the upper face of which constitutes a field. At each side of the field there is located an upstanding wall or flange 2. The game board and its surrounding wall form a shallow box-like container.

40 At the center of the field there is a circle 3. Upstanding partitions 4 disposed diametrically with regard to the circle, intersect at right angles so that the circle and the partitions coöperate to form four sectoral areas 5 defined on two sides by the partitions and on their third sides by the arcs of the circle. The partitions 4 are preferably parallel to the walls 2, and are confined entirely within the circle.

Associated with the field and movable thereon are a pair of eccentrically movable devices in the form of the conventional weighted tumblers 6, each having one red 55 end and one blue end. These particular colors may of course be varied to suit the trade. A suitable caption 7 such as the words "Safety zone" may be displayed within in the circle 3. 60

Several games which are designated as "Safety first" may be played with the apparatus. For instance the box may be held by the operator in either one or both hands and tilted to cause both tumblers to stand 65 erect in one of the compartments of the safety zone with the same colored ends up; or the box may be manipulated to cause both tumblers to stand erect in different compartments of the safety zone. 70

Owing to the eccentric movement characteristic of the weighted tumblers, it is very difficult to assemble them in upright position within the central areas so that the game will prove difficult as well as interesting. 75

80 The particular number of tumblers to be used is immaterial, and obviously various other slight changes and alterations might be made in the general form and arrangement of the board and men without departing from my invention, and hence I do not limit myself to the precise details set forth, but consider myself at liberty to make such changes and alterations as fairly fall within 85 the spirit and scope of the appended claim.

What I claim is:

85 In a game apparatus, a shallow rectangular box-like container, the base of said container forming a field having a centrally disposed circle thereon, diametrically opposed upstanding intersecting partitions parallel to the wall of the container, and dividing the circle into sectors, a plurality 90 of weighted tumblers adapted to be actuated by tilting the field, said circle having displayed therein a caption including the words "Safety zone." 95

ALBERT O. COULLIARD.
